UNITED STATES PATENT OFFICE.

SIDNEY JAS. SYDNEY, OF BOSTON, MASSACHUSETTS, ASSIGNOR OF ONE-FOURTH TO EMILE MULLER, OF NEW ORLEANS, LOUISIANA.

MARINE-ENGINE GOVERNOR.

SPECIFICATION forming part of Letters Patent No. 671,983, dated April 16, 1901.

Application filed November 29, 1899. Serial No. 738,709. (No model.)

To all whom it may concern:

Be it known that I, SIDNEY JAS. SYDNEY, a citizen of the United States, residing at Boston, in the county of Suffolk and State of Massachusetts, have invented certain new and useful Improvements in Marine-Engine Governors; and I do hereby declare the following to be a full, clear, and exact description of the invention, such as will enable others skilled in the art to which it appertains to make and use the same.

My invention relates to improvements in marine-engine governors, and more especially to an electrically-operated governor by means of which racing of the engines of a vessel is prevented when the propeller rises out of the water. In order to accomplish this result, my said invention embodies the novel arrangement and combination of parts hereinafter more particularly described and claimed.

Referring to the accompanying drawings, which illustrate my said invention, Figure 1 represents in fragmentary side elevation a vessel equipped with my improved governor. Fig. 2 represents, on a smaller scale, a rear elevation of a vessel equipped with my improved governor. Fig. 3 is an enlarged detail view of one of the solenoids and steam-pipe valve, showing the two connected. Fig. 4 is an enlarged detail view of one of the solenoids connected to the link-reversing mechanism of the engine, and Fig. 5 is a diagram of the electric circuit.

Similar letters refer to similar parts throughout the several views.

A represents a vessel, and B its engines, which drive the propeller C. At the stern of the vessel and preferably on each side thereof are the metallic plates D, secured to the outside of the vessel and insulated therefrom, as at d. These plates extend downward to a point about on a line with the center of the propeller and upward a short distance above the vessel's water-line. The plates D are electrically connected in series with a rheostat E, the solenoids F and H, and with the electric generator or ship's dynamo G.

The solenoid F is provided with a core f, which is connected through the lever-arm f⁰ to the valve-rod f' of the reversing-engine F'. The piston-rod f² of the reversing-engine

is connected to the link mechanism f³ in the usual manner. A spring f⁴ is mounted at one end of the solenoid F and normally engages one end of the core f, the spring being held in a bracket f⁵.

The construction of the solenoid H is substantially the same as the solenoid F, having the core h and spring h', held in the bracket h²; but in this instance the core of the solenoid is connected by a link h³ to the operating-arm h⁴ of the main steam-pipe valve h⁵.

The operation of the device is as follows: The resistance of the electric circuit is so adjusted by the rheostat E that so long as the vessel is on a level keel or the propeller is at its proper depth in the water, and hence as long as the plates D are submerged to a corresponding extent, the current flowing over the circuit will be sufficient to cause the solenoids F and H to draw in their cores against the tension of the springs f⁴ and h' to such an extent that the reversing-engine valve-rod f' will be pulled to that position where the links will be set for the forward motion of the ship or for the backward motion, if the case requires it, and the steam-pipe valve h⁵ will be opened. When, however, the stern of the vessel rises, the resistance between the plates D will be increased and the current flowing through the solenoids will be diminished in exact proportion to the rise of the stern of the vessel, and as a consequence the core of each solenoid, acting under the tension of the springs f⁴ and h', will operate upon the reversing-engine and steam-pipe valve of the main engine and cause the steam to be cut off gradually and the links to be moved toward the central position, reducing the speed of the main engine in proportion to the rise of the propeller. As soon as the stern of the vessel falls again the reverse action will take place, when the steam-pipe valve will be opened and the engine again started. The resistance between the plates will thus vary according to the depth to which the plates are submerged. When the vessel is loaded, the resistance of the circuit will be lower than when it is not loaded, though the vessel is on a level keel, as is obvious; but this difference in the resistance of the circuit may be compensated for by the rheostat E.

Instead of controlling both the reversing mechanism and steam-pipe valve it is obvious that I may employ only one of these at one time—that is to say, I may govern the engine by operating the steam-pipe valve alone without interfering with the reversing mechanism; nor do I confine myself to the exact location of the plates D as shown, as the same may be varied without departing from the spirit of my invention. Thus, for example, when the vessel is of wood or other non-conductor the plates would be placed one upon the other, while if the vessel has a metallic hull the plates would be arranged preferably as shown in Figs. 1 and 2. There are many other obvious changes that might be made in my said invention without departing from the spirit thereof; but

What I claim, and desire to secure by Letters Patent of the United States, is—

1. In a marine-engine governor, the combination with the main steam-pipe valve, of a solenoid, operative connection between said steam-pipe valve and said solenoid, a source of electric current electrically connected to said solenoid, a water-rheostat connected in the circuit with said solenoid and comprising two fixed conductors secured to the outside of the stern of the vessel and in contact with the water, the resistance between said conductors being varied in proportion as the stern of the vessel is submerged, and a rheostat in the circuit with said solenoid for adjusting the normal resistance of the said circuit, substantially as described.

2. In a marine-engine governor, the combination with a reversing-engine having a lever for operating the valve thereof, of a solenoid,

operative connection between said reversing-lever and said solenoid, a source of electric current electrically connected to said solenoid, a water-rheostat connected in the circuit with said source of current and solenoid, said rheostat comprising two fixed conductors secured to the outside of the stern of the vessel and in contact with the water, the resistance between said conductors being varied in proportion as the stern of the vessel is submerged, and a rheostat in the circuit with said solenoid for regulating the normal resistance of the circuit, substantially as described.

3. In a marine-engine governor, the combination with the valve for admitting driving fluid to the engine and the mechanism for reversing said engine, of a solenoid operatively connected to said valve, and a solenoid operatively connected to said reversing mechanism, a source of electric current electrically connected to said solenoids, a water-rheostat comprising two fixed conducting-plates secured to the outside of the stern of the vessel and in contact with the water, said plates being connected in said electric circuit, said water-rheostat governing the flow of current through the coils of said solenoids in proportion as the stern of the vessel is submerged, a rheostat located in the circuit with said solenoids for adjusting the normal resistance of the circuit, substantially as described. 70

In testimony whereof I affix my signature in presence of two witnesses.
